BUSINESS MACHINE

Robert L. Muller, Detroit, Mich., assignor to Burroughs Adding Machine Company, Detroit, Mich., a corporation of Michigan

Application June 1, 1936, Serial No. 82,731
Renewed December 24, 1937

24 Claims. (Cl. 197—128)

This invention relates to a line finding device for business machines and more particularly to a directly visible line finder especially adapted to a Burroughs high keyboard bookkeeping machine. It has been customary with a machine of this type to sight a line finder by indirect means such as lights and reflecting mirrors. This was necessitated by the fact that the platen in this type of machine is positioned in back of and below the keyboard so that when a sheet is inserted under the platen, the printing line cannot be observed by the operator and the sheet cannot be adjusted readily for correct alignment.

Therefore, it is a general object of my invention to provide an improved line finding device.

Another object is to provide a line finding device for use on a machine of the high keyboard type that is directly visible to the operator during line finding operations.

20 A further object is to provide a directly visible line finding device suitable for a machine of the high keyboard type having a front feed paper carriage and operable, without adjustment, upon sheets varying as to size and form.

25 Still another object is to provide a directly visible line finding device that is adapted to facilitate the insertion of a journal sheet from the front or rear.

A further object is to provide a sheet end signal controlled line finding device.

30 Other objects and advantages of the invention will be made apparent hereinafter.

The nature of the invention will be more apparent from the following specification, in which one embodiment is illustrated. The invention is illustrated and described as applied to a Burroughs high keyboard bookkeeping machine of the type disclosed in the copending United States applications Serial Nos. 469,957 and 745,066, filed by Robert Muller and in the Burroughs British Patent No. 382,613 of July 23, 1930, and wherein is shown and described Burroughs high keyboard machines having front feed means and means for automatically and manually opening and closing the paper throat and front feed means. It will be understood that the directly visible line finder comprising the present invention is adaptable to both the manually and automatically operated throwback carriages, and is applicable to the entire general class of business machines of which the high keyboard machine is but one form.

In the drawings—

Figure 1 is a perspective view of a portion of a Burroughs high keyboard machine and illus-

trating the line finding device in aligning position;

Fig. 2 is a partial right side elevation illustrating the paper carriage with the right-hand side plates removed and showing the relative 5 positions of the parts when in printing position with the line finder in inoperative position;

Fig. 3 is also a partial right side elevation illustrating the paper carriage with the right-hand side plates removed and showing the relative 10 positions of the parts in throwback position and the line finding means in operating or line finding position.

Fig. 4 is a left side elevation illustrating the means for moving the carriage to open throat 15 position.

Fig. 5 is a partial right side elevation of the paper carriage illustrating the line finding device in combination with a sheet end signal device.

20

Machine generally

Referring to the drawings, there is illustrated the "Burroughs high keyboard" machine of the type shown in the aforesaid applications and British patent and having the usual platen 10 mounted in a platen supporting frame 11 and the customary feed rolls 12. The platen is movable from a printing position relative to the printing mechanism of the machine, as shown in Fig. 2, to a front-feed position as shown in Fig. 3. When the platen is in its front-feed position the feed or pressure rolls 12 are disengaged therefrom as shown in Fig. 3, and the platen may be said to be in front-feed position where the throat for receiving the papers is open. A front-feed paper table 13 is provided which is adapted to receive and guide a work sheet 14 into front-feed position and to assist in holding it as will presently appear. This table is pivotally mounted at 15 on the carriage frame 16 so that it normally tends to move counterclockwise, but its counterclockwise movement is limited, when the platen is in front-feed position, by a rubber bumper 17. As the platen is returned to printing position, the edge of one of the plates 11 of the platen frame engages rollers 18 on the table so as to swing the table to a substantially vertical position where the lower edge of the table assists in holding the inserted sheet about 50 the platen.

Means are also provided for automatically opening and closing the front feed throat and for moving the platen to and from printing position in the illustrated type of machine, as is disclosed 55

in said applications and British patent and will now be briefly described. As the machine is given a cycle of operation a cam 20 on the motor operated shaft 21 is rotated clockwise into engagement with a stud 22 carried by a lever 23 that is pivoted at 24 to the machine, thereby rocking the lever 23 counterclockwise and tensioning a spring 25 which constantly urges the lever 23 in a clockwise direction. As lever 23 is rocked counterclockwise, a slide 26 connected thereto by a link 27 is drawn downwardly where it is held by a latch 28^a adapted to be engaged and released by a stud 28^b carried by a bail 28. Upon being released, the slide 26 is moved upwardly by the spring 25. The upward movement of the slide 26 raises a bail 28 carried by a pair of levers 29 to rock the levers 29 clockwise. The forward ends of levers 29 are connected to arms 30 fixed to a shaft 30^a, which is rocked counterclockwise by levers 29, thereby raising the platen 10, its frame 11 and the table 13 to open throat or front feed position. As the platen frame 11 is returned counterclockwise (Fig. 2) into printing position, the table 13 moves in a clockwise direction into a more nearly vertical or closed throat position by the engagement of the rollers 19 with the curved edges of the platen supporting frames 11.

The machine also provides for automatic line spacing for each transaction in the well known manner as well as for automatic movement of the platen 10 and table 13 to and from open throat position, as was briefly described above.

The visible line finding device is especially adapted to aligning ledger or work sheets to the desired printing line, but at the same time it is equally well adapted for the alignment of journal sheets. The work sheets are usually inserted and withdrawn after each line of printing, while the journal sheet remains around the platen for a continuous record of all items entered on the work sheet. The line finding device embodying my invention will first be described in connection with the alignment of a work sheet.

45 Line finder—front feed insertion of work sheet

With the platen 10 in front feed or open throat position and with the table 13 in forward or open throat position, as shown in Fig. 3, the work sheet 14 is placed upon the table 13 and then moved downwardly between the platen 10 and the feed rolls 12 into printing position. In this position it is apparent that the surface of the sheet upon which the printing is done is facing downwardly and hence cannot be observed by the operator. However, the work sheet may be moved to a visible and more vertical position by my aligning device which provides an aligning means in relation to which the work sheet may be vertically adjusted by the operator into correct alignment for the next printing line.

This aligning device comprises a blade 31 which extends across the width of the carriage (Fig. 1) and which is formed with and supported by integral left and right arms 32 and 33, the arms being pivoted to the table 13 at 34. The arms terminate in finger levers 35 and 36 at their upper ends for moving the blade 31 to the operative or aligning position (Fig. 3). To move the line finder to operative or line finding position, the finger levers 35 and 36 are moved manually counterclockwise thereby causing the blade 31 to move counterclockwise about pivots 34 until the forward portion of the work sheet has been raised to a substantially vertical position with the rearward edge of the blade 31 serving as the line

finder for indicating the printing line. The line finding device may be latched in this position while the operator adjusts the sheet vertically until the rearward edge of the blade extends just under the previous line of figures as in Fig. 1. 5 When this alignment is achieved the work sheet is in aligned position for printing the next transaction on the line below the one sighted with the aligning blade. The blade 31 is preferably notched as at 37 in order that a set of figures may 10 be observed below the line finder during line finding operations. This insures that the edge of the line finder is aligned with the last printing line and precludes any possibility of error.

The means for releasably latching the blade 31 15 in operative or aligning position comprises a stud 38 located on a rearwardly extending portion 39 of the blade supporting arm and is adapted to slide in a T-shaped slot 40, the vertical portion of which is arcuate, formed in a lever or latch 41 20 pivoted to table 13 at 42. A tension spring 43 (Fig. 3) attached to the stud 38 and to a lever 44 pivoted at 42 to the table 13 constantly urges blade 31 clockwise out of aligning position and the stud 38 downwardly toward the lower end of the T-shaped slot 40. Another spring 45, tensioned between a stud 46 located on the central portion of latch 41 and a stud 47 located on the forward end of the lever 44, urges lever 44 clockwise. Lever 44 is limited in this movement by a circular opening 48 therein through which extends a fixed 30 limiting stud 49 carried by the table 13.

When the machine is in open throat position, the lever 44 is maintained in counterclockwise position against the clockwise urge of spring 45 35 by a stud 54 carried by a lever 52. Consequently, when line finder 31 is moved counterclockwise to line finding position stud 38 will rise to the horizontal portion of T-slot 40, whereupon the spring 45 may rock the latch 41 counterclockwise until 40 stud 38 reaches the rear end of the horizontal portion of T-slot 40 (Fig. 3) and thereby latch line finder 31 in operative or line finding position.

After the work sheet has been adjusted to the correct printing line, the aligning blade 31 may be 45 either manually or automatically caused to move to inactive position. To manually release the blade 31, an upwardly extending handle portion 50 of the latch 41 is moved rearwardly by the operator so as to move the latch 41 in a clockwise 50 direction until the stud 38 enters the vertical portion of the T-shaped slot and has been restored under the urge of the spring 43 from its latched position in the horizontal portion to its normal position in the vertical portion of the slot, 55 thereby returning the blade 31 to inoperative position.

Automatic release of blade 31 to inoperative position is accomplished when the throat is closed and the platen is returned to printing position. 60 As the platen frame 11 is moved counterclockwise from the position of Fig. 3 to that of Fig. 2, a rod 51 carried by the platen frame engages the lever 52 pivoted at 53 to the carriage frame 16 and rocks lever 52 causing the stud 54 thereon to move 65 upwardly and permit lever 44 to rock clockwise. As this occurs a forward edge of a notch 55 of the lever 44 engages the stud 46 to move latch 41 clockwise until the stud 38 enters the vertical portion of T-slot 40 and is returned by the spring 70 43 into the vertical portion of the slot. This permits the blade 31 to return clockwise to inoperative position.

Thus, in the operation of the machine, the blade 31 must be manually moved to line finding

position by the operator, but after the proper alignment of the work sheet it may be manually or automatically released. The manual release is especially desirable and necessary when it is found that a wrong work sheet has been inserted and that it is necessary to remove the same.

When the carriage and its associated parts are in printing position (Fig. 2) lever 44 is maintained approximately in the central position of its limited movement by stud 54 carried by lever 52. With the platen in this position, lever 44 holds latch 41 in released position through the spring 45. That is, should the aligning blade 31 be moved counterclockwise into aligning position, the stud 38 will not slide into the horizontal portion of the T-shaped slot 40 so as to latch the blade in aligning position.

When the platen frame 11 is returned to front feed position (Fig. 3), rod 51 carried by the platen frame 11 moves rearwardly and allows the lever 52 to move counterclockwise about its pivot, thereby causing the stud 54 to move lever 44 counterclockwise. This movement of lever 44 causes the forward side of the notch 55 to move away from the stud 46 and causes the spring 45 to exert a counterclockwise urge on latch 41. The stud 38 at this time is in the vertical portion of the T-slot 40 and prevents relative movement between lever 44 and latch 41. Then, when the aligning blade 31 is brought into aligning position, after the work sheet has been inserted into the open throat, and stud 38 is raised and enters the upper horizontal portion of the T-shaped slot, latch 41 will be permitted to be moved forwardly or counterclockwise by the spring 45, causing the stud 38 to be latched in the rearward end of the horizontal portion of the T-shaped slot as shown in Fig. 3 and the stud 46 to again contact the forward side of the notch 55.

40 Line finder—Front fed journal sheet

Although the line finding mechanism operates substantially in the same manner in the alignment of a journal sheet as in the alignment of a work sheet, the insertion of the journal sheet at the front or rear presents slight variations in the operation and handling of the machine. To adjust the machine for the insertion of the journal sheet through the open throat at the front 50 of the carriage, the carriage is moved to open throat position of Fig. 3 and then a paper pan 60 carried by a shaft 61 is moved counterclockwise to the dot-dash position shown in Fig. 5. This facilitates the feeding of the journal sheet 55 around the platen and over shaft 61 instead of under the shaft 61 as is done with the work sheet. The forward portion of the paper pan is constantly urged into contact with the platen 10 by a spring 63 that is attached to the end of 60 a lever 65 fastened on shaft 61. The paper pan 60 presses the journal sheet against the platen and aids in maintaining the journal sheet in fixed position during the insertion of work sheets 65 when the feed rolls are disengaged from the platen and in open throat position.

To swing the paper pan 60 out of contact with the platen, a hand lever 66, pivoted to the side of a journal table 64 as at 67 is manually rocked rearwardly or clockwise. Lever 66 has an integral arm which engages a stud 68 carried by a lever 69 pivoted on shaft 61, and rocks lever 69 counterclockwise until stud 68 is received in a notch 70 of lever 66 to thereby latch lever 69 in counterclockwise direction. Another lever 71, 75 fixed to the shaft 61, is yieldingly connected by

a spring 72 to lever 69, whereby movement of lever 66 will rock shaft 61 so as to move the paper pan 60 counterclockwise out of engagement with the platen.

With the paper pan 60 in inactive dot-dash position (Fig. 5), the journal sheet is easily inserted at the front and fed down between the platen 10 and the feed rolls 12, rearwardly over the pan 60, and onto the journal table 64. At this point the forward portion of the journal sheet is resting with its printed surface downward on the table 13. Similar to the operation in aligning work sheets, the blade 31 is now moved counterclockwise, thereby raising the forward portion of the journal sheet to a vertical 15 position where it is aligned by the operator to the desired printing line by means of the rearward edge of the blade 31.

After the journal sheet is properly aligned, finger lever 66 is then manually released by 20 rocking it counterclockwise to release the stud 68 from the notch 70 and to permit the paper pan 60 to move clockwise, thereby forcing the journal sheet into engagement with the platen. As the lever 66 is rocked counterclockwise the 25 lever 69 also moves clockwise, thereby permitting arm 71 to do likewise and allowing the shaft 61 to rotate so as to move the pan 60 into contact with the journal sheet. The forward portion of the sheet may then be placed under a 30 blade 73 carried by lever 52 and then under a spring-pressed feed roll 74 (Fig. 3) so as to prevent interference with the work sheet.

Line finder—Rear fed journal sheet

35

When the journal sheet is to be inserted from the rear of the machine, such being the case when a continuous roll journal is used, certain elements of the machine must be moved out of active position to provide a clear pathway for 40 the sheet in its passage into the correct aligned printing position around the platen. With the machine in open throat position, the paper pan 60 is moved away from the platen to the inoperative dash dot position of Fig. 5, by moving 45 the hand lever 66 clockwise and latching the same, this operation being the same as previously described for front feed insertion of the journal sheet. The blade 73 is removed to inoperative position, that is, rearwardly, by depressing a slide 75 (Figs. 2 and 3) slidably mounted on lever 52 by means of studs 76 which project from lever 52 and extend into slots 77. A spring 78 tensioned between the lever 52 and the slide 75 normally urges the slide in a forward direction to maintain a hooked end 79 of slide 75 in locked engagement with the shaft 51 when in open throat position. Depression of the slide 75 causes the hooked end 79 to become disengaged from shaft 51 so that the blade 73 60 and the lever 52 may be freely moved rearward or clockwise.

After the paper pan 60 and the blade 73 have been removed to inoperative position, the journal sheet is inserted from the rear and moved forward under the platen where its forward edge is guided upwardly in front of the platen by a shield 80. Further progress of the journal sheet, however, may be interfered with by contact with the line finder which is in its normal inactive 70 position. To prevent such interference the line finder 31 may be manually removed from its normal inactive position, in a clockwise direction to the retracted dot-dash position of Fig. 5, at which point the journal sheet may be manually 75

moved forward by the operator until its forward edge passes above the line finder 31. The line finder 31 is yieldingly held against movement beyond its normal inactive position of Figs. 1 and 5 by a bell crank lever 81 pivoted at 34 and urged counterclockwise, as viewed in Fig. 1, against a limit stud 82 by a spring 83. The upper arm 85 of this lever is in the path of a stud 84 on an extension of one of the side arms which 10 carries the line finder 31. When the line finder is in its normal position the stud 84 contacts the lever 85. When it is desired to move the line finder beyond normal the finger piece 35 is pushed rearwardly. This finger piece is fixed to 15 one of the side arms that supports the line finder and is formed at a more vertical angle than the finger piece 36. As the operator pushes on the finger piece 35 the line finder is moved beyond normal in a clockwise direction, the stud 20 84 engaging arm 85 and rocking bell crank 81 against the tension of spring 83.

With the blade in this retracted position, the journal sheet is moved further forward until its forward portion is passed over the line finder 31 at which point the line finder may be released to 25 normal inoperative position. Then the line finder may be moved counterclockwise to aligning position so as to raise the forward end portion of the journal sheet to a vertical position for alignment 30 to the correct printing line.

Since the lever 52 is moved to the rearward position for the rear insertion of a journal sheet, the stud 54 of the lever 52 is not actively positioned to contact the lever 44 so as to cause the 35 latching of the line finder in aligning position as it is in front feed insertion. The line finder 31 is latched in operative position without the use of the lever 52 and its stud 54 because as the line finder 31 is moved counterclockwise to aligning 40 position against the journal sheet, the spring 43 urges the lever 44 in a clockwise direction which in turn urges the latch 41 also in a clockwise direction so that the stud 38 slides up the vertical portion of the T slot 40 and into the forward 45 end of the horizontal portion instead of the rearward end portion as in the case of front insertion of a journal sheet.

After the journal sheet has been aligned into correct printing line, the paper pan 60 is released 50 to engage the journal sheet and hold it against the platen by moving the finger lever 66 counterclockwise. The lever 52, carrying the blade 73, is manually returned to active forward position where its stud 54 engages the lever 44 to release 55 the stud 38 from its latched position in the forward end portion of the T-shaped slot 40 and to enable the line finder 31 to return to inoperative position. The line finder 31 may also be returned to normal position manually by moving the handle portion 50 of the lever 41 in a counterclockwise direction to disengage the stud 38 from its latched position before returning the lever 52 to active forward position. The forward portion of 60 the journal sheet may then be placed under the auxiliary feed roll 74.

Sheet end signal

There is also provided in the present invention a sheet end signal device which is adapted to prevent latching of line finder 31 in aligning position when the journal sheet nears its last printing line. In other words, the line finder is combined with a sheet end lock in such a way that when the operator rocks the line finder 31 into aligning position, it will not be latched therein in po-

sition as is usually the case, but will return immediately to inoperative position, thereby warning the operator that a new journal sheet is required. For this purpose a pawl or sensing means 86 (Fig. 5) is journaled on a shaft 87 and has an upper arm 88 in constant engagement with the forked end 89 of a lever 90. Lever 90 is pivotally mounted on the shaft 51 and has a forwardly extending arm 91 carrying a stud 92 in position to be received in a notch 93 in a curved and downwardly extending arm 94 of the latch 41. A spring 95 tensioned between shaft 87 and the lever 90 urges lever 90 in a clockwise direction and, thereby through the arm 88 urges the pawl 86 counterclockwise toward pan 60 and into engagement with the journal sheet 62. After the journal sheet has been fed out of contact with the pawl 86, the pawl, under the urge of spring 95 drops counterclockwise into a slot provided for this purpose in the paper pan 60. Simultaneously, 10 lever 90 is rocked clockwise so that stud 92 engages the notched arm 94 of the latch 41 with the result that the latch 41 is locked in inoperative position so that the line finder 31 cannot be 15 latched in aligning position, although it may be 20 moved thereto.

It is desirable that the operator be able to latch the line finder in aligning position even though the rearward edge of the journal sheet has passed the pawl 86 as when the operator wishes to print 25 on the line below that in printing position when the sensing pawl 86 drops. To return the lever 90 and the pawl 86 to inoperative position, there is provided a lever 96 which is fixed on the shaft 87 and has a slot 97 through which extends shaft 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 I claim:

1. In a business machine, a platen, a front-feed chute for receiving and guiding a sheet under the platen to printing position, said chute being movable relative to said platen from a sheet-receiving to a sheet-holding position and vice versa, a line finding device pivotally carried by said chute and movable independently thereof to and from line finding position, means for moving the line finding device to line finding position while said chute remains in sheet-receiving position, means for releasably holding said line-finding device in line-finding position, and means for returning said line finding device to inoperative position in so far as line finding is concerned.

2. In a business machine, a platen, a front-feed chute above and forward of said platen for receiving and guiding a sheet under the platen to printing position, said chute being movable relative to said platen from a sheet-receiving to a sheet-holding position and vice versa, a line finding device pivoted to said chute and movable independently thereof to and from line finding position, manual means for moving the line finding device to line finding position while said chute remains in sheet-receiving position, means for releasably holding said line-finding device in line-finding position, and automatic means for returning said line finding device to inoperative position in so far as line finding is concerned.

3. In a business machine, a platen, a front-feed chute for receiving and guiding a sheet to printing position, said chute being movable relative to said platen from a sheet-receiving to a sheet-holding position and vice versa, a line finding device pivoted to said chute and movable independently thereof to and from line finding position, means urging said line-finding device to a position where it is inactive for line finding, means for moving the line finding device to line finding position, means for latching the line finding device in line finding position and means automatically operable for releasing said latch to permit said line finding device to return automatically to inactive position in so far as line finding is concerned.

4. In a business machine, a platen, front-feed means movable to and from front-feed position for receiving and guiding a front-fed sheet to printing position, a line finding device pivoted to said front-feed means for movement therewith and movement independently thereof to and from line finding position, means for moving the line finding device to line finding position, means for latching the line finding device in line finding position, and means automatically operable upon movement of said front-feed means to closed throat position for causing said line finding device to return to inoperative position.

5. In a business machine, a platen, a front-feed means for receiving and guiding a sheet to printing position, a line finding device, means for moving said line finding device to line finding position, latching means adapted to latch the line finding device in line finding position, a sheet controlled means governed by the presence of a sheet in contact with a portion of said means, and connections between said latch and said sheet controlled means adapted to prevent the latching of the line finder in line finding position when a sheet is not in engagement with said portion of said sheet controlled means.

6. In a business machine, a platen, a front-feed means for receiving and guiding a front-fed sheet

to printing position, a line finding device, means for moving said line finding device to line finding position, latching means adapted to latch the line finding device in line finding position, a sheet end signal means, connections governed by said sheet end signal means adapted to prevent the latching of the line finder in line finding position when said sheet end signal is in one position, means for moving the sheet end signal means from said position to permit the latching of the line finding device in line finding position, and means for releasing said latch to permit said line finding device to move to inoperative position.

7. In a business machine having front-feed means movable to open and closed throat position for receiving and guiding a front-fed sheet to printing position, a line finding device, means for moving said line finding device to line finding position, latching means adapted to latch the line finding device in line finding position, a sheet end signal device, connections governed by said sheet end signal device adapted to maintain the said latching means in inoperable position when said signal device is in one position, means for moving the sheet end signal device from said position to permit the latching of said line finding device in line finding position, and means automatically operable upon closing of said throat to release said latch to permit said line finding device to move to inoperative position.

8. In a business machine, a front-feed means adapted to be moved to and from open throat position, a line finding device pivoted to said front-feed means comprising a blade extending laterally of the machine and adapted to be used in aligning a sheet to the correct printing line by the adjustment of the sheet relative to the rear edge of the blade, means for moving said blade to line finding position while said front-feed means remains in open throat position, means for releasably holding said line-finding device in line-finding position, and means operable automatically to return said blade to inoperative position upon movement of said front-feed means to closed throat position.

9. In a business machine, a platen frame, a platen supported by said frame, a front-feed paper table, a pivoted line finding device comprising a blade extending laterally of the machine in front of said platen and adapted to be used in aligning a sheet to the correct printing line, means normally urging said line finder to inoperative position, means yielding limiting said latter means, and means for moving said blade in one direction to line finding position, said blade being movable in the other direction against said yielding means.

10. In a business machine, a platen frame, a platen supported by said frame, a front-feed paper table, a pivoted line finding device pivoted to said table comprising a blade extending laterally of the machine in front of said platen and adapted to be used in aligning a sheet to the correct printing line, means normally urging said line finder to inoperative position, means yielding limiting said latter means, and means for moving said blade in one direction to line finding position, said blade being movable in the other direction against said yielding means.

11. In a business machine, a platen frame, a platen supported by said frame, a front-feed paper table adapted to support and guide a paper sheet, a line finding device pivoted to said table comprising a blade extending laterally of the ma-

chine in front of said platen and adapted to align a sheet to the correct printing line, means for moving the blade to line finding position, latching means adapted to latch the line finding device in line finding position, means for releasing said latch to permit said line finder to return to inoperative position, a sheet end signal device, and connections governed by said sheet end signal device adapted to prevent the latching of the line finding device in line finding position when said signal device is in one position.

12. In a business machine, a platen frame, a platen supported by said frame, a front-feed paper table adapted to support and guide a paper sheet, a line finding device pivoted to said table comprising a blade extending laterally of the machine in front of said platen and adapted to align a sheet to the correct printing line, means for moving the blade to line finding position, latching means adapted to latch the line finding device in line finding position, a sheet end signal device, connections thereto adapted when in one position to prevent the latching of the line finding device in line finding position, means for moving said sheet end signal device out of said position to permit the latching of the line finding device in sheet aligning position, and means for releasing said latch to permit said line finding device to move to inoperative position.

13. In a business machine, a platen frame, a platen supported by said frame, front-feed means including a paper table adapted to support and guide a paper sheet, a line finding device pivoted to said table comprising a blade extending laterally of the machine in front of said platen and adapted to align a sheet to the correct printing line, means to move the blade to line finding position, latching means adapted to latch the line finding device in line finding position, a sheet end signal device adapted to engage the latching means so as to disable said latch when said device is in one position, means for latching said sheet end signal device in ineffective position to permit the latching of the line finding device in sheet aligning position, and means for releasing said latch to permit said line finding device to return to inoperative position.

14. In a business machine, a platen adapted to be moved to and from printing position, a front-feed means for receiving and guiding a sheet to printing position, a paper pan adapted to support a sheet during insertion and to maintain the same against the platen when in operative position, means for moving said pan to inoperative position, a line finding device adapted to align a sheet to the correct printing line, means for moving the line finding device to line finding position, means adapted to latch the line finding device in line finding position, a sheet end signal device adapted to prevent the latching of the line finding device in line finding position when in one position, a single means cooperating with the paper pan moving means and said sheet end signal device whereby said paper pan and said sheet end signal device are moved simultaneously, and means for releasing said latching means to permit said line finding device to return to inoperative position.

15. In a business machine, a platen adapted to be moved to and from printing position, a front-feed means including a paper table adapted to support and guide a paper sheet, a line finding device pivoted to said table comprising a blade extending laterally of the machine in front of said platen and adapted to align a sheet to the correct printing line, means for moving said

blade to line finding position, latching means adapted to latch the line finding device in line finding position, a sheet end signal device adapted to prevent the operation of said latching means, a paper pan adapted to support a sheet during insertion and to maintain the same against the platen when in active position, latching means for moving said pan to inactive position, a single means cooperating with the paper pan moving means and said sheet end signal device whereby said paper pan and said sheet end signal device are moved simultaneously, and means for releasing said latch to permit the line finding device to return to inoperative position.

16. In a business machine, a platen, a front-feed chute movable to and from front-feed position relative to said platen for receiving and guiding a sheet under the platen to printing position, a line finding device movable independently of said chute to and from line finding position, means for moving said line finding device to line finding position while said chute is in the front-feed position, means for releasably holding said line-finding device in line-finding position and automatic means for returning said line finding device to inoperative position.

17. A machine of the class described having a platen, front-feed means for receiving and holding a work sheet in front-fed position relative to said platen, said front-feed means providing a throat that is movable from a closed to an open-throat position and vice versa and having portions that enable a sheet to be positioned face forward in said throat while it is open, a line finder normally occupying a position where it is inactive for line finding, means for moving said line finder to a line-finding position independently of said front-feed means and while said front-feed means is in front-feed position, holding means for releasably holding said line finder in line-finding position said line finder having portions acting, when so moved, to move the upper end of an inserted work sheet to a substantially vertical position and to releasably hold said sheet about said platen to enable said sheet to be adjusted to line position and to be held in such position by said line finder, and means operable to close said throat to grip said work sheet as so held and to then cause said line finder to be moved automatically to inactive position.

18. A machine of the class described having a platen, front-feed means for receiving and holding a work sheet in front-fed position relative to said platen, said front-feed means providing a throat that is movable from a closed to an open-throat position and vice versa and having portions that enable a sheet to be positioned face forward in said throat while it is open, a line finder urged to a position where it is inactive for line finding, means for moving said line finder to a line-finding position independently of said front-feed means, said line finder having portions acting, when so moved, to move the upper end of an inserted work sheet to a substantially vertical position and to releasably hold said sheet about said platen to enable said sheet to be adjusted to line position and to be held in such position by said line finder, means for holding said line finder in line-finding position, and means operable to close said throat to grip said work sheet as so held and to subsequently disable said line-finder holding means.

19. A machine of the class described having a platen, front-feed means for receiving and hold-

ing a work sheet in front-fed position relative to said platen, said front-feed means providing a throat that is movable from a closed to an open-throat position and vice versa and having portions that enable a sheet to be positioned face forward in said throat while it is open, a line finder urged to a position where it is inactive for line finding, means for moving said line finder to a line-finding position independently of said front-feed means, 5 said line finder having portions acting, when so moved, to move the upper end of an inserted work sheet to a substantially vertical position and to releasably hold said sheet about said platen to enable said sheet to be adjusted to line position 10 and to be held in such position by said line finder, means for holding said line finder in line-finding position, and means operable to close said throat to grip said work sheet as so held and to subsequently disable said line-finder holding 15 means, the disabling portion of said means acting to maintain said holding means disabled until said throat is again opened.

20. A machine of the class described having a platen, front-feed means for receiving and holding a work sheet in front-fed position relative to said platen, said front-feed means providing a throat that is movable from a closed to an open-throat position and vice versa and having a paper chute that enables a sheet to be placed face downward in an inclined position in said throat while it is open, said chute being movable from a sheet-receiving to a sheet-holding position and vice versa, a line finder normally occupying a position where it is inactive for line finding, means for moving said line finder to a line-finding position independently of said paper chute, said line finder having portions acting, when so moved, to move the upper end of an inserted work sheet to a substantially vertical position and to releasably hold said sheet about said platen to enable said sheet to be adjusted to line position and to be held in such position by said line finder, holding means for releasably holding the line-finder in line-finding position and means operable to close said throat to grip said work sheet, to move said chute from sheet-receiving to sheet-holding position, and to cause said line finder to be moved automatically to inactive position.

21. A machine of the class described having a printing mechanism, a platen movable from a printing position relative to said printing mechanism to a front-feed position and vice versa, front-feed means associated with said platen for enabling a work sheet to be received and held in front-fed position relative to said platen, said front-feed means providing a throat that is movable from a closed to an open-throat position and vice versa and having portions enabling a sheet to be placed face forward in said throat while it is open, a line finder normally occupying a position where it is inactive for line finding, means for moving said line finder to a line-finding position independently of said front-feed means and while said front-feed means is in front-feed position, holding means for releasably holding said line finder in line-finding position, said line finder having portions acting, when so moved, to move the upper end of an inserted work sheet to a substantially vertical position and to releasably hold 5 said sheet about said platen to enable said sheet to be moved to, and to be held by said line finder, in line position, and means for closing said front-feed throat and moving said platen to printing position including means operating automatically after said front-feed throat has been closed to disable said line-finder holding means and to maintain it disabled until said platen is moved to front-feed position.

22. A machine of the class described having a printing mechanism, a platen movable from a printing position relative to said printing mechanism to a front-feed position and vice versa, front-feed means associated with said platen for enabling a work sheet to be received and held in front-fed position relative to said platen, said front-feed means providing a throat that is movable from closed to open-throat position and vice versa and having portions enabling a sheet to be placed face forward in said throat while it is open, a line finder urged to a position where it is inactive for line finding, means for moving said line finder to a line-finding position independently of said front-feed means, said line finder having portions acting, when so moved, to move the upper end of an inserted work sheet to a substantially vertical position and to releasably hold 10 said sheet about said platen to enable said sheet to be moved to and to be held by said line finder, in line position, holding means for holding said line finder in line-finding position, and means for closing said front-feed throat and moving said platen to printing position including means operating automatically after said front-feed throat has been closed to disable said line-finder holding means and to maintain it disabled until said platen is moved to 15 front-feed position.

23. A machine of the class described having a printing mechanism, a platen movable from a printing position relative to said printing mechanism to a front-feed position and vice versa, front-feed means associated with said platen for enabling a work sheet to be received and held in front-fed position relative to said platen, said front-feed means providing a throat that is movable from closed to open-throat position and vice versa and having portions enabling a sheet to be placed face forward in said throat while it is open, a line finder urged to a position where it is inactive for line finding, means for moving said line finder to a line-finding position independently of said front-feed means, said line finder having portions acting, when so moved, to move the upper end of an inserted work sheet to substantially vertical position and to releasably hold said sheet about said platen to enable said sheet to be moved to, and to be held by said line finder, in line position, holding means for holding said line finder in line-finding position, and means for closing said front-feed throat and moving said platen to printing position including means operating automatically after said front-feed throat has been closed to disable said line-finder holding means and to maintain it disabled until said platen is moved to front-feed position.

24. A machine of the class described having a printing mechanism, a platen movable from a printing position relative to said printing mechanism to a front-feed position and vice versa, front-feed means associated with said platen for enabling a work sheet to be received and held in front-fed position relative to said platen, said front-feed means providing a throat that is movable from a closed to an open-throat position and vice versa and having a paper chute enabling a sheet to be placed face downward in an inclined position in said throat while it is open, said chute being movable from sheet-receiving to sheet-holding position and vice versa, a line finder normally occupying a position where it is inactive for line finding, means for moving said line finder to line-finding position independently of said front-feed throat and moving said platen to printing position including means operating automatically after said front-feed throat has been closed to disable said line-finder holding means and to maintain it disabled until said platen is moved to front-feed position.

paper chute, holding means for releasably holding the line-finder in line finding position said line finder having portions acting, when it is so moved, to move the upper end of an inserted work sheet to a substantially vertical position and to releasably hold said sheet about said platen to enable said sheet to be moved to, and to be held by said line finder, in line position, and means for

closing said front-feed throat and moving said platen to printing position and said chute from sheet-receiving to sheet-holding position including means operating automatically after said front-feed throat has been closed to cause said line finder to be moved to its inactive position. 5

ROBERT L. MULLER.
